UNITED STATES PATENT OFFICE

SAMSON M. WECKSTEIN, OF CANTON, OHIO, ASSIGNOR TO THE TIMKEN ROLLER BEARING COMPANY, OF CANTON, OHIO, A CORPORATION OF OHIO

TUBE MILL

Application filed April 30, 1930. Serial No. 448,496.

My invention relates to piercing mills. With mills of this type, the hot billet is fed by suitable means endwise against the head of a piercing mandrel which is located between 5 rotating rollers whose axes are in planes parallel to the axis of a mandrel but inclined in opposite directions in their respective planes. The rollers are widest about midway of their length and taper towards 10 their ends; and they are spaced apart at such distance that the periphery of the billet will come in contact therewith about half-way (more or less) between the forward ends of the rolls and the middle thereof, the point 15 of the piercing mandrel being located slightly forward in the middle of the rolls. Under these conditions, the end of the billet is forced forwardly and against the plane of the mandrel, whereby the diameter of the billet is reduced sufficiently to pass between the widest 20 portion of the rolls, beyond which the spreading action of the conical mandrel spreads the metal outwardly against the surface of the rear half of the roller. In the early action, 25 the billet is forced against the forward half of the roller and the thrust must be taken care of by the bearings of the rollers; but later on the thrust of the metals being spread by the mandrel is in opposite direction and this 30 thrust must also be taken care of by the bearings of the rollers. On account of the intense heat and the severe stresses to which the rollers are subjected, the wear on the bearings 35 has been rapid and it has been difficult and expensive to keep the rollers journaled with the precision required to produce satisfactory work. The principal object of the present invention is to overcome these difficulties. The invention consists in interposing roller 40 bearings between the roll necks and head supports, such bearings being adapted and arranged to take care of the stresses thereon being adjustable for wear and arranged to accommodate themselves to the variations of 45 temperature and to aid in dissipating the heat that the roll necks might absorb. It also consists in providing suitable roller bearings for the thrust block. It also consists in the combinations and arrangements of parts hereinafter described and claimed.

In the accompanying drawings wherein like reference numerals refer to like parts wherever they occur,

Fig. 1 is a plan view of the thrust block, and the table on which it slides,

Fig. 2 is a plan view of a piercing mill of well known type, being a continuation of Fig. 1,

Fig. 3 shows a detail sectional view of a reeler roll,

Fig. 4 is a sectional side view of the thrust block,

Fig. 5 is a side view partly in section of a mandrel bar with a piercing plug,

Fig. 6 is a sectional view taken in the middle of a piercing roller stand,

Fig. 7 is a side view partly in section of the piercing roller and stand,

Fig. 8 is a detail sectional view of a piercing mill roll, and

Fig. 9 is an elevation of the thrust block.

The piercing mill illustrated in the accompanying drawings is of a well known type (with the exception of the bearings of the thrust block and rollers) and it is therefore considered unnecessary to describe the same in detail. In general the mill comprises a set of rollers 1 suitably mounted, a guide table 2 for the tube after it has been rolled, and a thrust block 3 that is slidable to and from the rollers. The rollers are journaled in bearings (hereinafter described) that are covered by any suitable housing. The roll housing 4 is mounted on a circular slideway 5, said slideway being mounted upon an upright housing member 6, said upright housing member being mounted upon two channel shaped base members 7 and 7' that extend the width of the roll stand. The roll housing 4 is flanged at each end to receive said circular slideway member and any suitable mechanism is used for moving the roll housing in relation to the slideway. This arrangement provides a means for adjusting the obliquity of the rolls. Each of the drive shafts 8 which are driven by a common source as is customary in the construction of piercing mills, are attached to the roller shafts 8' by universal joints 9.

Mounted crosswise upon the two base mem-

bers in the center and directly between the rollers is a framework 10, said framework being provided with a trough shaped under guide member 11 directly between the two rollers at the center. Mounted at the fore end of said framework is an upright supporting member 12 and integral with said member is a cylindrical guide member 13 that guides a billet 14 to the rollers. The rear end 5 of said frame is provided with a second supporting member 15 that is provided with a trough shaped member 16 directly in line with the forward support, and constitutes a guide for the tube 17 after it has been rolled. Directly between the two rollers and in alignment with the rear and forward guide members and mounted upon a framework 18 extending horizontally from the upright housing is an upper guide member 19 which is adjacent and cooperates with the under guide 10 to hold the billet in position as it is being rolled. Each of these guide members is provided with notches 20 and 20', their forward ends adapted to receive the ends of two levers 21 and 21', said upper guide lever 20' being fulcrumed upon the upper framework, and said lower guide lever 20 being fulcrumed upon the lower crosswise framework. Mounted on the upper framework is a screw 22 15 that engages the top end of the top lever and similarly a screw 23 is mounted upon the lower framework and engages the lower end of the lower lever, both of which constitute means for adjusting the center guide members. 20

Positioned endwise in relation to the rear guide member is the long guide table 2 that is provided with trough shaped members suitably mounted on said table and which become 25 guide members 24 for the tube after it has been rolled. The table is also provided with bearings 25 on which are mounted a shaft 26 that is provided with arms 27 which extend slightly underneath the tube and form the means for lifting the tube and throwing it off to the side after said tube has been rolled and a mandrel bar 28 has been drawn out. One 30 end of the mandrel bar 28 is provided with a suitable piercing plug 29, while the other end engages a shaft 30 that is mounted in a housing 31 of the thrust block 3 of well known type. The thrust block is provided with two springs 32 placed on either side that engage bumpers 33 at the rear of the thrust block 35 so that the tube upon striking the forward end of the thrust block will be cushioned by the action of the springs. The thrust block is slidable upon two angle bars 34 suitably mounted on a base 35, which forms a slideway 40 for the thrust block. Spaced at intervals along said slideway are horizontal shafts 36, rollers 37 being rotatably mounted thereon. Said rollers carry a rod 38 extending the length of the slideway, one end of said rod 45 being secured to the thrust block, the other

end being attached to any suitable mechanism for moving the thrust block along the slideway. The slideway is provided at the rear end with two cylindrical casings 39 that contain compression springs 40, said springs being provided with bumpers 41 for stopping the thrust block at the rear end of its travel. 50

Instead of the bearings commonly used for the shaft 30 of the thrust block, the present invention makes use of roller bearings at the front and rear portions of such shaft. Said shaft is of greatest diameter at its forward end and is stepped down near its forward end to form a shoulder 42 for the forward bearing, and again stepped down towards its rear end to form a shoulder 43 for the rear bearing. The front bearing comprises a duplex cone 44 mounted on the shaft and positioned by a spacing ring 45 interposed between it and the forward shoulder of said shaft. This duplex cone has a rib 46 about midway of its length and also ribs 47 at its ends, the portions between the end ribs and the middle rib being formed into conical raceways 48 with their large diameter next to the middle rib. On each of the raceways is a series of conical rollers 49 mounted in suitable cages 50 and cooperating respectively with cups 51 or other raceway members. One of these cups 51' is mounted in a seat 52 in the cartridge 53 that has a cylindrical inner surface and has a key or spline 54 mounted on its outer surface and fitting in a key-way 55 cut longitudinally in the inner surface of the housing. 55

The outer end of said cartridge extends inwardly over said spacing ring, an oil closure 56 being interposed between them. The other cup or outer bearing member 51 also fits in the open end of said cartridge and is positioned by an adjusting ring 57 that is secured to the end thereof and has a flange 58 that extends inwardly against said cup. A positioning ring 59 bears against the inner end of said cone and is held in place by means of cap screws 60 that have threaded engagement with the shaft. 60

The outer bearing comprises a spacing ring 61 mounted on the reduced portion of the shaft and bearing against the shoulder thereon. Also mounted on the shaft and bearing against this spacing ring is a cone or bearing member 62 that has a thrust rib 63 on its large end, being the end next to the spacing ring; and cooperating with the conical bearing surface of said cone is a circular series of conical rollers 64 mounted in a suitable cage 65 and cooperating also with a cup or outer bearing member 66. This cup is mounted in an annular seat 67 provided therefor in said housing. Rearwardly of said seat the housing is reduced in diameter and at some distance further rearwardly the inner diameter of the housing is increased to form an annular seat 68 for 65 70 75 80 85 90 95 100 105 110 115 120 125 130

a cup or outer raceway member 69 for a circular series of rollers 70 mounted in cages 71 and rolling in contact with the raceway of a cone or inner bearing member 72 that is mounted on the still further reduced end portion of said shaft and is provided with ribs 73 next to its raceway. This inner bearing member is held in position by a sleeve or resistance member 74 which is mounted on the shaft and is provided with rings or other suitable washers 75 and is itself positioned by a locking nut 76 that has screw-threaded engagement with the end of the shaft and is secured by tongued lock washers 77 or the like, together preferably with an additional locking nut.

The shell is provided with an oil port 78 through which oil or lubricant may be applied to the interior thereof, and as the oil rings serve to block the passage of oil lengthwise of the shaft, it is obvious that a considerable quantity of oil may be applied inside the large chamber between the two oil rings.

By the arrangement described, the bearings may be readily adjusted. The forward bearing, meaning to include the two series of rollers on the duplex cone, may be adjusted by means of shims 79 between the end of the cartridge and the positioning flange interposed between the end of the cartridge and the flanged ring secured thereto. The rear bearing, meaning to include the two series of rollers (on the rear part of the shaft) may be adjusted by manipulation of the threaded nut on the threaded end of the shaft.

In the operation of a piercing mill, the principal function of the thrust block is to receive the endwise thrust on the billet and to allow rotation of the billet on the longitudinal axis that maintains its position with precision. In this operation, the bearings are subjected to heavy endwise thrust as well as to radial load. According to the present construction, the forward bearing is designed to take care of radial load principally but on account of the form of the rollers, the bearing is capable of also taking care of a reasonable amount of endwise thrust and is particularly adapted for maintaining a true central alinement of the shaft throughout a considerable range of adjustment of the bearing for wear or position. On the other hand, the rear bearing is designed to take care of the principal endwise thrust; and for this reason the rollers of the forward of the two series at the rear of the shaft are exceptionally large and heavy, and the inner bearing cone is made exceptionally thick so as to enable more of such rollers to be mounted in the series. In consequence of the foregoing arrangement the bearings of the thrust block are much more durable than the usual bearings and throughout their life can be kept precisely adjusted for alinement and position.

The main piercing mill rolls are journaled on the usual rotatable cradles. Instead of being journaled in plain bearings, each end of the shafts is journaled and each main piercing mill roll is provided with roller bearings interposed between it and the cradles in which it is mounted. In the particular construction illustrated, two sets of duplex roller bearings are shown on each end of each shaft 8'. Each of the duplex bearings comprises a duplex cone or inner bearing member 80 mounted directly on the shafts and provided with a thrust rib 81 midway of its length, from which the raceways or bearing surfaces 82 taper towards the ends, a circular series of tapered rollers 83 cooperating with each of said raceways and themselves mounted in suitable cages 84, and a cup or outer raceway member 85 for each series of rollers. The two duplex cones at each end of the shaft are spaced apart by a distance piece 86 in the form of a ring mounted on the shaft and the duplex cone nearest to the roll at each end thereof is positioned by a sleeve or filler ring 87 mounted on the shaft, with its ends bearing respectively against said duplex cone and said main piercing mill roll. Another spacing ring 88 is mounted on a shaft between the driving head of the shaft and the adjacent duplex cone. The duplex cone at the other end of the shaft is positioned by means of a perforated plate or ring 89 that is held by means of cap screws 90 that have threaded engagement with the end of the shaft, the margin of said plate or ring overlapping the ends of the outermost duplex cone and contacting therewith. By this engagement, the tightening of said cap screws forces the outermost duplex cone inwardly and the movement thereof is transmitted through the spacing ring to the next duplex cone and thence through the spacing ring to the driving head of the shaft. In this manner, all of the parts that are mounted directly on the shaft are firmly positioned relative to each other. The duplex cones are also provided with notches 91 next to the shaft at their outside ends which engage projections 92 in the spacing rings and hence prevent the bearings from turning on the shaft.

The bearing cups or outer raceway members are seated in a bearing cartridge 93 in the form of a shell with cylindrical inner and outer surfaces. About midway of the length of this cartridge or shell is a rib 94 integral therewith on the inner surface thereof, and this rib together with the inner surface forms annular seats for the cups or raceway members of two series of rollers. The cups or outer raceway members for the two series of rollers at the driving end of the shaft have a sliding fit in the respective ends of the cartridge; and each of these outer raceway members is held in place by clamping rings 95 that overlap the ends of the car-

tridge and have annular ribs 95' that fit in the interior of the cartridge and are adapted to bear against and form abutments for the outer raceway members in the respective 5 ends of the cartridge. The peripheral portions of these rings overlap the respective ends of the cartridge and are secured thereto by suitable means. It is obvious that metal shims may be interposed between said rings 10 and the respective ends of said cartridge to provide for the adjustment of the bearings. The inner surfaces of these rings are provided with grooves 96 in which are fitted felt rings 97 or oil proof washers that contact 15 with the outer surfaces of the spacing rings on the shaft. Such rings close the ends of the chamber in which the roller bearings are located and to which oil or lubricant may be supplied through a passageway that extends 20 therefrom through the top of the bearing cartridge and the cradle in which it is mounted. At the outer end of the shaft are a cartridge, outer raceway members therein and 25 positioning rings screwed to the ends of the cartridge, all similar to those at the driving end of the shaft and described in the preceding paragraph, except that the endmost ring is made in the form of an enclosing plate 98 that covers the entire end of the 30 shaft and except that such plate does not have the groove for the oil ring above described.

The ends of each of the bearing cartridges 35 93 or shells, each of which is preferably made of a single piece, are provided with annular ribs 99 on the ends of their outer surfaces. Each of these cartridges or shell is mounted in a cylindrical seat 100 provided therefor in the roll housing 4, with the ribs at the 40 ends of the cartridge overlapping the ends of the seat. In the case of the housing next to the driving end of the shaft, the sides 101 of the ribs bear snugly against the ends of the cradle seat, whereby the bearing at the driving end of the shaft is fixed in position. At the outer end of the shaft, however, the 45 ribs of the cartridge are spaced further apart than the length of the seat, and consequently do not prevent longitudinal or axial movement of the bearings at the outer end of the shaft. This arrangement enables the bearings to accommodate themselves automatically to the expansion of the shaft arising 50 from the heat incident to the working of the mill. This is due to the fact that although the cartridge that holds the bearings at the driving end of the shaft is fixed in its position, the cartridge that encloses bearings at the opposite end of the shaft is free to float 55 endwise.

Fig. 3 shows a modification using roller bearings in place of plain bearings on reeler rolls 102, said reeler rolls being mounted in the usual manner. Instead of being journaled in plain bearings, each end of the 60

reeler roll shaft 103 is journaled and each reeler roll is provided with roller bearings interposed between it and the cradles in which it is mounted. Two sets of duplex roller bearings are provided on each end of 70 each shaft. Each of the duplex bearings comprises a duplex cone 104 mounted directly on the shaft and provided with a thrust rib 105 midway of its length and also a rib 106 at each end, said ribs bordering 75 raceways 107 which taper toward the ends. A circular series of tapered rollers 108 cooperates with each of said raceways, said rollers being mounted in a suitable cage 109. Each of the two outside series are provided 80 with a cup 110 or outside raceway, while the two center series of rollers have for an outside raceway a duplex cup 111 tapering from the middle to the ends. The two duplex cones at each end of the shaft are spaced 85 apart by a spacing member 112 in the form of a ring mounted on the shaft, and the duplex cone nearest to the roll at each end thereof is positioned by a filler ring 113 mounted on the shaft, with its ends bearing 90 respectively against said duplex cone and said reeler roll. Another spacing ring 114 is mounted on a stepped down portion of the shaft between the driving head and the adjacent duplex cone. The duplex cones are 95 provided with notches 115 next to the shaft at their outside ends which engage projections in the spacing rings and hence prevent the bearings from turning on the shaft. The duplex cone at the end of the shaft opposite 100 the driving head is positioned by means of a plate 116 secured to the end of the shaft by cap screws 117, said plate 116 overlapping the ends of the outermost duplex cone and contacting therewith or with shims interposed.

The outer raceway members are seated in a cartridge 118 in the form of a shell, said cartridge being provided with annular flanges 119 at each end nearest the working 110 roll that cooperates with the filler ring. Said flange is provided with two annular grooves 120, one on its bottom and one on its side in which fit oil seal rings 121 thus providing an oil seal between inside of the 115 shell and the filler ring. The raceway members for the two series of rollers at the driving end of the shaft have a sliding fit in respective ends of the cartridge and each of them is held in place by a clamping ring 122 120 that overlaps the ends of the cartridge and has annular ribs that fit in the interior of the housing and adapted to bear against the outer raceway members in the respective ends of the housing. The outside portions of these 125 rings overlap the ends of the housing and are secured thereto by cap screws 123 that extend through them and through metal shims 124. The inner surface of this ring is provided with an annular groove in which 130

is fitted an oil proof washer 125. At the outer end of the shaft are a housing, outer raceway, members therein and positioning rings secured to the ends of the housing, all 5 similar to those at the driving end, except that the endmost ring 126 is made in the form of an enclosing plate that covers the entire end of the shaft and does not have an oiling ring groove. Each of the bearing 10 housings is mounted in a spherical seat 127 provided in the cradle and a vertically disposed pin 128 extends from the cartridge into a rectangular recess 129 in the roll housing 4 whereby rotation of the cup carrier is 15 prevented. The cradle is secured to any suitable framework in a manner well known in tube mill construction.

What I claim is:

1. A tube piercing mill comprising a frame- 20 work, roll housings thereon, piercing rolls having their axes at oblique angles to each other and whose neck portions extend through the respective housings, conical roller bearings interposed between the respective 25 roll neck portions and housings and arranged to take endwise thrust in both directions, means for driving the respective rolls on the same side of said framework, the roll housings at the driving end of said roll being 30 fixed on said framework and the roll housings at the other ends being movably mounted on the framework, a thrust block, a shaft therein, and a mandrel bar engaging said shaft and associated with said rolls.

35 2. A tube piercing mill comprising a framework, roll housings thereon, a set of piercing rolls having their axes at oblique angles to each other and whose neck portions extend through the respective roll housings 40 and conical roller bearings interposed between the respective roll neck portions and housings, each bearing including a plurality of duplex cones mounted on a neck portion, cooperating cups, rollers interposed between 45 said cones and cups and adjustable means for firmly positioning the bearing parts on the roll neck portion relative to each other.

3. In a tube mill, a framework, roll housings thereon, and a piercing roll having its 50 neck portions extending in the roll housings, the roll housing at the driving end of said roll being firmly secured on the framework and the roll housing at the other end being movably mounted on the framework to allow 55 for expansion of the roll due to heating thereof.

4. A tube piercing mill comprising a framework, roll housings thereon, piercing rolls whose neck portions extend through the 60 respective roll housings, a thrust block, having a housing, a shaft extending from said thrust block housing, a mandrel bar engaging said shaft and operatively associated with said rolls, a large conical thrust bearing 65 interposed between said shaft near its inner

end and the thrust block housing, and conical roller bearings interposed between the forward end of said thrust block housing and the shaft designed principally for radial loads.

5. A tube piercing mill comprising a framework, piercing rolls mounted thereon, a mandrel bar associated with said rolls, a thrust block, having a housing, a shaft extending from said thrust block housing and operatively connected to said mandrel bar, antifriction bearings interposed between said shaft and the thrust block housing comprising at the end that receives the mandrel bar a duplex cone mounted on said shaft, two outside cups mounted in said housing, rollers interposed between said cone and cups, a single cone near the other end of the shaft, a single outer cup mounted in an annular seat in said housing towards the thrust, and large rollers adapted to receive the thrust interposed between said cone and cup, another cone mounted on a still further reduced portion of the shaft, a single outer cup and rollers interposed between said cone and cup. 80

6. A tube mill comprising a framework, roll housings thereon, a set of rolls having their axes at oblique angles to each other and whose neck portions extend through their respective roll housings, conical roller bearings interposed between the respective roll neck portions and housings, each bearing including two duplex cones, two single outer cups, a duplex cone spaced midway between said single cups, and rollers interposed between said cones and cups. 90

7. A tube piercing mill comprising a framework, piercing rolls, a mandrel bar operatively associated with said piercing rolls, a thrust block, a housing therefor, a shaft extending from said thrust block and operatively connected to said mandrel bar, conical roller bearings designed principally for radial loads interposed between said shaft and the thrust block housing near its forward end, means for adjusting said bearing, a conical roller bearing designed principally for thrust loads interposed between said shaft and housing near its inner end, and means for adjusting said thrust bearings. 105

8. A tube mill comprising a framework, roll housings thereon, a set of rolls having their axes at oblique angles to each other and mounted on shafts whose ends extend through the respective housings, conical bearings interposed between the respective shaft ends and housings, each bearing at the driving head including two duplex cones mounted on said shaft, three cups mounted on said housing, rollers interposed between said cones and cups, similar cones, rollers and cups provided at each of the ends opposite the driving head, a plate secured to each of the outer ends of the shaft by means of cap screws, said plate overlapping the shaft 110 115 120 125 130

in each case and forming abutments for the outer duplex cones, whereby turning the cap screws forms a means for adjusting said bearings.

- 5 9. A tube piercing mill comprising a framework, a set of piercing rolls, a thrust block having a housing whose inner periphery is reduced and then increased near its inner end to form annular seats, a shaft extending from said thrust block housing and having a reduced portion near its inner end to form a shoulder, a mandrel bar engaging said shaft and operatively associated with said rolls, cups mounted in the housing and having their larger ends abutting against the annular seats, respectively, cones mounted on the shaft to cooperate with said cups, the outermost cone having its larger end abutting against the shoulder on said shaft, rollers interposed between said cones and cups, a sleeve mounted on said shaft and abutting against the most rearward cone and an adjusting lock nut having threaded engagement with the end of said shaft and abutting 25 against said sleeve.

Signed at Canton, Ohio, this 25th day of April 1930.
